CLAIM

The ornamental design for a cowling for an outboard motor, as shown and described.

DESCRIPTION

FIG. 1 is a front perspective view of a cowling for an outboard motor showing our new design.

FIG. 2 is a rear perspective view thereof.

FIG. 3 is a side view thereof.

FIG. 4 is an opposite side view thereof.

FIG. 5 is a front view thereof.

FIG. 6 is a rear view thereof.

FIG. 7 is a top view thereof; and,

FIG. 8 is a bottom view thereof.

The broken lines in the drawings illustrate portions of the cowling for an outboard motor that are not part of the claimed design. The claim is directed to the solid lines only, which provide shape to, and define the contours of, the claimed design. The claimed surfaces do not extend to the broken lines.
